FIRE EXTINGUISHER

Frederick S. Brennan, Wilmette, Ill., Carl Jones, Jr.,
Menominee, Mich., and Merritt R. Bauman, Marinette,
Wis., assignors to The Ansul Company, Marinette, Wis.,
a corporation of Wisconsin

Filed July 20, 1965, Ser. No. 86,215

Term of patent 14 years

(Cl. D16—2)

FIG. 1

FIG. 2

FIG. 3

FIG. 4

FIGURE 1 is a side elevation of a fire extinguisher showing my new design;

FIGURE 2 is an elevation rotated 90° counterclockwise from FIGURE 1;

FIGURE 3 is a top plan view thereof; and

FIGURE 4 is a fragmentary elevation taken from The characteristic features of my design reside in the specific configuration of the extinguisher handle member in association with a conventional cylindrical casing as shown.

We claim:

The ornamental design for a fire extinguisher, substantially as shown and described.
